UNITED STATES PATENT OFFICE.

HUGH P. McMILLAN, OF BALTIMORE, MARYLAND, ASSIGNOR TO WM. A. TOTTLE & CO.,
A FIRM COMPOSED OF WILLIAM A. TOTTLE AND MORTON P. TOTTLE, OF BALTI-
MORE, MARYLAND.

BRUSH.

1,105,573.

Specification of Letters Patent. Patented July 28, 1914.

Application filed October 11, 1910. Serial No. 586,426.

To all whom it may concern:

Be it known that I, HUGH P. McMILLAN, a citizen of the United States, residing at Baltimore, in the State of Maryland, have 5 invented certain new and useful Improvements in Brushes, of which the following is a specification.

This invention relates to improvements in brushes and has particular reference to a 10 brush for use in painting and decorating.

The object of the invention is to provide an improved construction of brush whereby to securely hold the bristles about and to the handle, and to protect the lower end of the 15 wood handle from the action of liquids that causes the wood to swell and break the cement or rubber binder.

The invention is illustrated in the accompanying drawing wherein,—

20 Figure 1 is a side elevation of a complete brush. Fig. 2, an enlarged vertical longitudinal section through the lower portion of the handle and the devices securing the same to the butt-ends of the bristles. Fig. 3 is a 25 vertical cross-sectional view of the same, and Fig. 4, is a perspective detail of the flanged central wedge.

In the drawing, 1, designates a wooden 30 block having an upwardly-projecting handle, 2, and a depending central plug or rib, 3. This plug or rib is long and narrow in a transverse direction and projects centrally from the bottom side of the block leaving an 35 overhanging shoulder, 4, on the wooden block along the opposite sides and around the ends of the plug.

The bristles, 5, have their butt ends, 6, bound together by a suitable cement or vulcanized rubber and said butt-ends are encircled by a suitable band, 7, to retain them. 40 A metal shell, 8, is provided at the center of the butt-ends of the bristles and has long side walls, 9, and narrow end walls, 10, both of which incline at their lower portion, 11, and merge. A horizontal flange, 12, is provided at the upper open end of the shell which projects outwardly over the butt ends of the bristles and toward the encircling band, 7. This flange, 12, is provided in the present 45 instance with a plurality of perforations, 13, which are disposed over the inner ends of

the bristles so that the cement or rubber when in a plastic condition can squeeze into said perforations and form a key to secure the shell-flange and bristle-ends together. 55

The plug or rib, 3, has its lower side and end portions inclined to correspond to the lower inclination of the side and end walls of the shell so it may snugly fit down therein and permit the overhanging shoulder, 4, on 60 the block to seat close on the horizontal flange, 12, of the metal shell. A suitable fastening such as a drive screw, 14, extends up through the closed inclined lower portion of the shell through the central plug, 3, and 65 into the block, 1, and fastenings, 15, extend horizontally from the band, 7, through the cemented ends of the bristles and also through the metal shell and central plug, 70 which fastenings, together with the drive screw, 14, securely hold the bristles and shell to the central plug. An outer ferrule, 16, encircles the block, 1, and also the band, 7, and is held to the block by means of nails, 17.

By means of this construction it will be 75 seen that the lower end of the block, 1, and plug, 3, which is formed of wood is covered with metal and is thereby protected from the action of liquids that often causes the wood to swell and consequently break or 80 crack the cement or hard rubber and the band that binds the ends of the bristles together.

Having thus described my invention what I claim and desire to secure by Letters 85 Patent is,—

A flat brush having a handle with a brush block at the inner end of the handle which block has a crosswise-extending narrow plug projecting downwardly from the center of 90 its under side which plug is of less width and thickness than the width and thickness of the brush block whereby to leave an integral overhanging shoulder on the block all the way around the narrow plug; a metal shell 95 having a long and narrow socket to receive the plug on the block and also having an integral outwardly-extending flange around its upper edge which flange is of less width than the overhanging shoulder on the block; 100 means extending into the plug from the under side of the shell socket to secure the shell

to the block; bristles having their butt ends around the sides and ends of the shell and beneath the integral outward flange of the latter; a band having an edge against the 5 overhanging shoulder of the brush block and its inner side seated against the edge of the outward flange of the shell and a ferrule around the band and the brush block and ex-

tending both below and above the flange on the shell.

In testimony whereof I affix my signature in presence of two witnesses.

HUGH P. McMILLAN.
